C. LE R. LANDIS,
NEEDLE SHAPING TOOL,
APPLICATION FILED FEB. 11, 1920.

1,405,045.

Patented Jan. 31, 1922.

Chester L. Landis ^{Inventor}

John J. Moore ^{Attorney}

UNITED STATES PATENT OFFICE.

CHESTER LE ROY LANDIS, OF READING, PENNSYLVANIA.

NEEDLE-SHAPING TOOL.

1,405,045.

Specification of Letters Patent. Patented Jan. 31, 1922.

Application filed February 11, 1920. Serial No. 357,853.

To all whom it may concern:

Be it known that I, CHESTER LE ROY LANDIS, a citizen of the United States, residing at Reading, in the county of Berks and State of Pennsylvania, have invented certain new and useful Improvements in Needle-Shaping Tools, of which the following is a specification.

This invention has reference to knitting machine needles, and in particular to that kind of needles which are provided with a friction groove, depression or the like at some part intermediate the ends of the needle, but ordinarily near the bearded or hooked part of the same for the purpose of retaining the meshes during and immediately after the interlacing of the new and old meshes, and my invention has for one of its objects to overcome the necessity of the bending of the needle shaft by hand which results in improper and irregular bends and improper friction, and in view of that it is another very important object of my invention to avoid the excessive dropping of stitches due to such improper friction, and to the bumping of the machine when such deficient needles are mounted upon a circular or other kind of knitting machine; and my invention is also intended to avoid other deficiencies in the making of the knitted fabric due to needles having improper friction, and to avoid the subsequent waste of knitting material, the formation of an excessive number of holes in the fabric, and the excessive repairs to the machines provided with such deficient needles. My invention has for one of its objects to avoid all these difficulties by providing means whereby the depression or friction groove or bend in the needles is always produced at the same distance from the hooked or similarly shaped end, and friction grooves and depressions of absolutely uniform shape may be obtained at all times. Other objects and advantages of my invention will appear from the specification, claims and annexed drawing.

In the drawing which represents by way of example a preferred form of embodiment of my invention

Figure 1 is a side view with a portion of the lever which forms a part of my invention, broken away.

Figure 2 is a top plan view of part of the device.

Figure 3 is an end view of the same, the lever being in section.

Figures 4, 5, and 6 are illustrations of a preferred form of needles which I may employ in connection with my device.

Figure 4 is a side view of a needle of the kind referred to, representing the flat side thereof.

Figure 5 shows the narrow side of the needle which is fitted into the machine.

Figure 6 is an illustration of the friction bend produced by the device forming the subject of this invention.

In the drawings:—5 is a base made of steel or of any other suitable material, 6 is a groove longitudinally provided in such base, and preferably milled in the edge of the base to admit the needle to be operated upon, 14 is a depression, socket or perforation in such base at about the point where the friction groove or depression is to be produced in the needle. 9 is an adjustable stop or abutment against which the head or end of the needle is placed before bending so as to adjust the exact position of the friction groove. An operating lever 2 is pivoted on the base 5 by means of a bolt 3 on block 4 which may be integral with the base 5 or adjustably secured thereto, the operating lever 2 in the case of the edgewise arrangement of the groove 6, being pivotally secured at one side of said base so as to be capable of engagement with said groove or with the needle inserted therein. 1 is an operating handle of wood or of other suitable material at the end of the lever 2. A projection, tooth or the like 7 is provided on the lever 2 adapted to fit the socket or depression 14 of the base, the sides of said projection 7 being preferably bevelled off as at 8 to correspond with correspondingly inwardly inclined sides of the socket or depression 14. The particular construction and configuration of the sides of the projection and of the socket, however, are not essential and may be changed to suit the convenience of the user. An adjusting screw 10 with setting nut 15 may be provided at some suitable point of the base 5, preferably near the end thereof, in order to be able to adjust and vary the stroke of the lever 2, and the distance or amount of mutual engagement of the projection 7 with the socket 14.

The needle is broadly indicated at 10'. It

has the depression or friction groove 12, and may be provided with a hook or beard 11, and a projection 13 at its other end by means of which it is fitted into the machine, as for instance into the cylinder of a circular knitting machine.

It is evident that the particular construction of the needle itself is not material for my invention, and it is to be understood that my invention is susceptible of various changes and modifications to suit the particular conditions of usage to which the invention is to be applied.

In view of the absolute uniformity of the friction groove produced by my invention, needles so prepared require less adjustment and attention on the part of the operator than those heretofore employed.

What I claim is:—

1. In a device for producing grooved needles, the combination of a base having a longitudinal groove and transverse depression, a lever pivoted to the base and having a projection to fit in the depression, an adjustable stop carried by said base to form an abutment for one end of the needle, and

means for regulating the throw of the lever and the entry of the projection into the depression.

2. In a device for producing grooved needles, the combination of a base having a longitudinal groove intersected by a depression, a stop forming an abutment for one end of the needle and adjustable with reference to the groove, a lever pivoted to the plate, a projection on the lever and adapted to enter the depression, and means for limiting the movement of the projection.

3. In a device for producing grooved needles, the combination of a base having a groove through the length of one edge and a transverse inclined sided socket, a stop disposed adjacent to the groove, a lever with a handle pivoted at one end of the base, an adjusting screw at the other end of the base to limit the movement of the lever, and a projection having beveled sides carried by the lever between the pivot and the adjusting screw and adapted to fit in the socket.

In testimony whereof I affix my signature.

CHESTER LE ROY LANDIS.
